UNITED STATES PATENT OFFICE.

JOHN VIVIAN, OF TRENTON, NEW YORK, ASSIGNOR OF ONE-HALF TO G. H. SKIFF, OF SAME PLACE.

WIRE-TIGHTENING DEVICE.

SPECIFICATION forming part of Letters Patent No. 372,723, dated November 8, 1887.

Application filed December 13, 1886. Serial No. 921,485. (No model.)

To all whom it may concern:

Be it known that I, JOHN VIVIAN, of Trenton, in the county of Oneida and State of New York, have invented certain new and useful 5 Improvements in Wire-Tightening Devices; and I do hereby declare that the following is a full, clear, and exact description of the invention, which will enable others skilled in the art to which it appertains to make and use the 10 same, reference being had to the accompanying drawings, and to the figures of reference marked thereon, which form part of this specification.

My invention relates to a device for tightening fence-wires; and it consists in the mechanism hereinafter described and claimed.

In the accompanying drawings, Figure 1 represents a front view of my wire-tightening device. Fig. 2 represents a similar view showing the pivoted lever in a different position from Fig. 1. Fig. 3 is a side view of Fig. 1. Fig. 4 is a section view on line x x , Fig. 3.

In constructing my improved wire tightening device I provide handle 1, of the required 25 length and size, with a sharpened or tapering end, 2. The tapering end is thus preferably constructed for piercing the wood forming the posts to which the wires are attached, and also for enabling the operator to insert the end in 30 the ground in cases where it may be found necessary in tightening the wire, or for holding the same in an upright position by sticking the same into the earth when not in use. On this handle I provide shoulder 3. For clamping 35 and holding the wire against the fixed shoulder on the handle, I provide the pivoted lever 5, pivoted to the handle at 6, which lever is free to move in either direction, the same being pivoted to the handle in such manner 40 that the circular face 4 is brought nearly in contact with the fixed shoulder, so that in grasping the wire between the shoulder and

the circular face of the lever the strain upon the wire tightens the lever, so that it clamps the wire rigidly. When the wire is thus 45 clamped, point 2 of the handle is placed against the post or other fixed object, and the operator crowds against the handle, thereby forming a powerful lever, which enables the operator to stretch the wire preparatory to 50 attaching the same to the post in the fence.

Another important feature of my invention consists in so constructing my wire-tightening device as to form shears for cutting the wire. This is accomplished by beveling the handle, 55 as shown in 7 7, Fig. 4, above the fixed shoulder, and in beveling the pivoted lever, as shown in 8 8, Fig. 4, above the circular face, the shearing-edges receding on either side toward the end of the lever, whereby the wire is 60 retained between the circular shearing-edge of the lever and the shearing edge on the handle. The operator moves the pivoted lever into position substantially at right angles from the handle and inserts the wire between the cutting-edges thus formed back of the circular face of the lever, which has the effect to retain 65 the wire from slipping on the cutting-edges formed as already described.

What I claim as new, and desire to secure by 70 Letters Patent, is—

The combination of the handle having a fixed shoulder and beveled shearing-edges above the shoulder, the lever having a semi-circular face projecting beyond the beveled edges, and the circular beveled edges above the semicircular face of the lever, the lever and handle pivoted to be operated, as set forth.

In witness whereof I have affixed my signature in presence of two witnesses.

JOHN VIVIAN.

Witnesses:

EDWIN H. RISLEY,
SARAH L. LINDSAY.
